UNITED STATES PATENT OFFICE.

AMOS G. MOORE, OF CHICAGO, ILLINOIS, ASSIGNOR TO THE MASON & MASON COMPANY, OF ILLINOIS.

DESIGN FOR A FORK AND CROWN FOR VELOCIPEDES.

SPECIFICATION forming part of Design No. 26,411, dated December 15, 1896.

Application filed November 3, 1896. Serial No. 610,984. Term of patent 14 years.

To all whom it may concern:

Be it known that I, AMOS G. MOORE, a citizen of the United States, residing at Chicago, in the county of Cook and State of Illinois, have invented and produced a new and useful Design for Forks and Crowns for Velocipedes, reference being had to the accompanying drawing, forming a part hereof.

In the accompanying drawing the figure is a perspective view of my design.

The leading feature of my design consists in a circular-shaped tubular portion arranged in a horizontal plane, and I form bosses or projections thereon at or near its end portions and at or near its central portion.

A is the circular curved tubular portion, arranged in a horizontal plane; B B, the shoulder projections at or near each end; C, an enlarged central portion, and E a vertical portion projecting therefrom, the whole presenting to the eye a harmonious and ornate figure, as shown in the accompanying drawing.

I claim—

The design for a fork and crown for velocipedes, substantially as herein shown and described.

AMOS G. MOORE.
